UNITED STATES PATENT OFFICE.

ALVARO MENDEZ, OF EAST ORANGE, NEW JERSEY, ASSIGNOR TO AMERICAN CAR AND FOUNDRY COMPANY, OF NEW YORK, N. Y., A CORPORATION OF NEW JERSEY.

STANCHION BRACKET.

Application filed September 8, 1927. Serial No. 213,208.

Reference is had to the accompanying drawings which illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a side elevation of the stanchion and bracket of the present invention in position in a car, a portion of the latter being diagrammatically shown;

Fig. 2 is a front elevation of a plurality of stanchions in use in a railway car, a portion of the latter being diagrammatically shown;

Fig. 3 is a top plan view of a plurality of stanchion brackets showing the stanchions in elevated position, or out of use;

Fig. 4 is a side elevation of a stanchion bracket with a portion of a stanchion in position therein;

Fig. 5 is a front elevation of the bracket shown in Fig. 4;

Fig. 6 is a sectional view on the line 6—6 of Fig. 5;

Fig. 7 is a sectional view on the line 7—7 of Fig. 5;

Fig. 8 is a front elevation of a modified form of stanchion bracket; and

Fig. 9 is a front elevation, partly in section, of the stanchion bracket of the present invention showing a portion of a stanchion in use and also in partially elevated position, the latter being shown in dotted lines.

This invention relates to stanchions and brackets therefor, and is designed especially for use in railway baggage cars under certain conditions, for example, when such cars are used for the transportation of mail or the like.

It is the primary object of this invention to provide a bracket for securely retaining a stanchion in use, and also to so form the bracket that it may support the end of an adjacent stanchion when the latter is in elevated or unused position.

A further object of the invention is to provide a stanchion bracket formed preferably of a single casting and hence easy and inexpensive to manufacture, and strong and durable in operation.

Other objects and advantages of this invention will be apparent from the following de-

scription taken in conjunction with the accompanying drawings, in which A indicates diagrammatically a railway baggage car having a roof B and a floor C. Countersunk in the floor C are the retaining cups 2 which receive the lower ends of the stanchions 4. The upper ends of the stanchions 4 are received within brackets 6, and as the brackets are identical, a description of one will suffice for all.

The brackets each comprise a casing 8 closed at one end by an attaching portion 10 by which the bracket is secured to a retainer 12 attached to the car roof B. The casing 8 is preferably, although not necessarily, cylindrical in shape and a spring 14 is positioned therein and bears against the attaching portion 10 and a plate 16 mounted on a rod 18 carried by the attaching portion; the latter being provided with a central depression 20 which receives the adjusting nut 22 mounted on the threaded end of the rod 18. As before stated, the upper end of the stanchion extends into the casing, and in Fig. 9, it can be seen that the plate 16 bears against the upper end of the stanchion 4.

The lower end of the bracket is of the form shown more clearly in detail in Figs. 4, 5 and 9, and comprises oppositely arranged guides 24 depending from the casing 8 and preferably cast integral therewith. For eliminating the side movement of the stanchion 4, a bearing collar 26 is provided which connects the guides 24 and provides what might be termed a closure for the lower end of the side face of the device; the opposite face being open to permit swinging of the stanchion as hereafter described. The stanchion 4 is provided with a stop member 27 which is attached thereto by a screw bolt 28 or the like, having a retaining nut 29, and said stop member is of a length sufficient to engage the guides 24 when the stanchion is in lowered position, as more clearly shown in Fig. 4.

Means are provided on the bracket for supporting the upper end of an adjacent stanchion, and the specific type shown in Fig. 4 comprises spaced arms 30 formed integral with one of the guides 24 and extending laterally therefrom; webs 32 being provided for reinforcing purposes. The lower arm 30 serves as a support or rest for the stanchion 5, the latter being the stanchion next adjacent the stanchion 4, and the arms 30 are provided with alined recesses 34 which

receive the ends of the stop member 27 of the stanchion 5. For restraining the stanchion 5 against accidental displacement, the upper arm 30 is provided with a lug 36 which pivotally mounts a latch 38 having an operating handle 40 and a stop member 42 adapted to contact with the upper face of the upper arm 30 both in latching and free positions. It will be apparent that when the stanchion 5 is in the position illustrated in Fig. 4, accidental displacement of the stanchion is prevented due to the positioning of the stop member 27 and the latch 38 which retains the stop member within the recesses 34.

Fig. 8 shows a modified form of bracket in which a socket 44 is formed with the casing, said socket being arranged substantially at right angles to the guides 24 and being adapted to receive the end of a stanchion adjacent the stanchion supported by this particular bracket. In the use of a bracket of this type, the stanchion is provided with openings through which a suitable securing pin 46 extends, the latter being also extended through the guides 24. It will be apparent that accidental displacement of the stanchion when in elevated position is prevented by the pin 46 which is inserted through the guides 24 and the stanchion after the latter has been elevated with the end thereof received within the socket 44.

Fig. 2 shows the stanchions in use the lower ends thereof being positioned in the cups 2 and the upper ends retained in the casing 6. When it is desired to elevate the stanchions to place them out of use, each stanchion is raised against the tension of the spring 14 until the lower end of the stanchion clears its cup, and then the stanchion is swung sufficiently to permit it to lower outside of the cup. This lowering of the stanchion will permit the upper end of the stanchion to clear the lower end of the casing 8 when the stanchion is swung or elevated. The stanchion is then elevated to the position shown in Fig. 2 and pushed rearwardly through the guides riding on the bearing collar 26 until the upper end of the stanchion is seated on the lower arm 30 of the next adjacent bracket, the parts then assuming the position shown in Fig. 4. The latch 38 having previously been swung to the dotted line position shown in Fig. 4 permits the stop element 27 to enter the recesses 34, whereupon the latch element 38 may then be swung to the full line position shown in Fig. 4 to restrain the stanchion against accidental displacement.

From the above description, it is believed that those skilled in the art will appreciate that this invention provides a stanchion bracket which will securely retain the stanchion in engagement with the cup 2 and also provides a construction which will securely retain an adjacent stanchion in elevated position and against accidental displacement.

What is claimed is:

1. A device of the kind described comprising a casing receiving the upper end of a stanchion, guides depending from the casing, and means formed integral with one of said guides for supporting an adjacent stanchion.

2. A device of the kind described comprising a casing for receiving the end of a stanchion, guides formed with said casing, a supporting element extending laterally from one of said guides, and means on said supporting element for retaining an adjacent stanchion thereon.

3. A device of the kind described comprising a stanchion receiving casing, yielding means in said casing engaging the stanchion for retaining the latter against displacement, a supporting element attached to the casing, and means for retaining an adjacent stanchion thereon.

4. A device of the kind described comprising a casing having connected depending guiding portions, a stanchion positioned between said guiding portions and extending into the casing, yielding means in the casing engaging the stanchion, a retainer bar on the stanchion engaging said guiding portions, means formed with one of said guiding portions for supporting a second stanchion, and a locking means for retaining said second stanchion on said support.

5. A device of the kind described comprising a casing for attachment to a car roof or the like to receive the end of a stanchion, yielding means in said casing engaging the stanchion end, a retainer element secured to the stanchion and engaging said casing, a supporting element formed with the casing for receiving the end of an adjacent stanchion and the retainer element thereof, and a latch carried by said supporting element and adapted to be positioned adjacent the retainer element of said adjacent stanchion to maintain said adjacent stanchion on the support.

6. In combination with a railway car having a roof, a plurality of stanchions, brackets secured to the roof of the car for receiving the upper ends of said stanchions, and means formed on each of said brackets for receiving the upper ends of adjacent stanchions to support the latter in elevated position.

7. In combination with a railway car having a roof and a floor, a plurality of stanchions, means in the floor for receiving the lower ends of the stanchions, brackets secured to the roof for yieldingly receiving the upper ends of the stanchions, a supporting element formed with each bracket for receiving the upper end of an adjacent stanchion when the latter is in elevated position, and a latch on said supporting element for retaining the stanchion therein.

8. In a railway car having stanchions, means for supporting said stanchions in elevated position, each comprising a casing for

attachment to the car and yieldingly receiving the end of a stanchion, a laterally extending support formed with the casing for receiving the upper end of an adjacent stanchion, and means for locking the adjacent stanchion to its support.

9. In a railway car, stanchions each having a retainer bar adjacent the upper end thereof, and stanchion supporting means each comprising a casing receiving the upper end

of a stanchion, oppositely arranged guides formed with said casing and with which the retainer bar contacts, means formed with the casing for receiving the upper end of an adjacent stanchion when the latter is elevated, and 15 a latch adapted to engage the retainer bar of said adjacent stanchion.

In witness whereof I have hereunto set my hand.

ALVARO MENDEZ.
